UNITED STATES PATENT OFFICE.

OTTO WEEBER, OF BERLIN, GERMANY, ASSIGNOR TO SIEMENS & HALSKE AKTIENGESELLSCHAFT, OF WERNERWERK, SIEMENSSTADT, NEAR BERLIN, GERMANY.

TELEPHONE DESK SET.

Application filed September 11, 1925, Serial No. 55,650, and in Germany December 5, 1924.

This invention relates to telephone desk sets and is directed particularly to the formation of the hand telephone support of such sets.

5 In the usual hand telephone sets having a movable telephone support, the latter is firmly connected at its central portion with a switching rod, which is loosely guided in the base assembly of the set, and according 10 as to whether the hand telephone is put on the support or removed therefrom, it acts by means of its axial displacement on contact springs of a switch arranged inside the set. As the hand telephone resting on the 15 support is heavier at one end than at the other, owing to the receiver portion having greater weight than the transmitter portion, an unequal loading of the support takes place which requires a suitable structure for 20 the hand telephone for the purpose of ensuring a satisfactory actuation of the switching rod. Therefore, hand telephone supports of the kind described do not allow the 25 application of light hand telephones.

Telephone sets are also known in which the support is firmly connected to the casing. In this arrangement the hand telephone resting on the support presses against a rod 30 displaceably arranged in the center of the support. The rod is shifted when the hand telephone is manipulated and influences according to its position contacts of a switch located in the casing.

This arrangement is substantially simpler 35 than the first mentioned, but it has disadvantages in so far as the switching rod adjoining the handle of the hand telephone prevents the grasping of the same, and when the hand telephone is replaced obliquely, its 40 weight is only partially used for the actuation of the rod. Thus the advantages of this arrangement as compared with the loose telephone support are partly lost by this drawback.

45 The invention now aims at an improved mode of operation. The hand telephone support is firmly connected to the casing, and has allocated to it several switching members acting upon a switching device inside the casing and controlled directly by 50 the hand telephone.

The switching members preferably in form of rods may be arranged at the two points of bearing of the hand telephone or else near the supporting members and act

upon a common radially movable bridge 55 which operates the contact springs of a switch arranged inside the casing.

The drawing, comprising Figs. 1 and 2, shows an embodiment of the invention.

Figure 1 is a front view of a desk set 60 with the telephone at rest, some of the parts being shown in section.

Figure 2 is a side elevation of the set 65 also partially in section, but with the telephone removed.

The drawing only shows those parts of the set which are essential for understanding the invention, while all remaining parts are left out for the sake of simplicity.

The casing 2 resting on the base 1 of the 70 station is provided at the top at each side with a fork projection 3. These projections are preferably made out of one piece with the casing 2, say of aluminum die cast or similar material. The two projections 3 75 form the support for the hand telephone 4 which in its normal position rests against the top of the rods 5 in the projections 3. These rods are movably located in openings of the projections 3 and protrude into the 80 interior of the casing. With the same effect, however, they can also be arranged against the projections. At their lower reduced ends 6, these rods rest against a plate 7 which is common to both rods and is rotatably mounted in the set. A spring urged rod 8 of the switching device 9, which includes also the switching springs 11, presses against the lower side of the plate 7. When the hand telephone is removed, the plate 7 90 is held by means of rod 8 in the position shown in Figure 2. The rods 5 project, in this position of the plate 7, beyond the bearing surface of the supports 3. If the hand telephone is put on the supports 3, then the 95 rods 5 come into position as shown in Figure 1 as a result of the weight of the hand telephone. This position is also shown in dotted lines in Figure 2, in which position the collar 10 of the switching device keeps 100 the contact springs 11 of the latter closed.

What is claimed is:

1. In a telephone desk set comprising a hand telephone and a base, a support for said hand telephone rigidly connected to said base, and a plurality of switching members projecting from said support and operable directly by said hand telephone as it rests on said support. 105

2. In a hand telephone desk set comprising a hand telephone and a supporting base, switching springs, a plurality of controlling members each directly operable by said hand telephone, and means directly controlled by each of said members individually for operating said springs when the hand telephone is positioned on the supporting base. 45
3. In a hand telephone desk set, switching springs, a member for operating said springs each time the hand telephone is placed on or removed from the support of the set, a plurality of switching means directly and individually operable by said hand telephone, and a single member intermediate to said first member and said plurality of switching means for operating said first member to operate said springs. 50
4. In a telephone desk set, a hand telephone, a base containing switching springs, forked extensions on said base for supporting said hand telephone, a plurality of operating members one of said members movably projecting midway between the prongs of each forked extension, and means directly controlled by each of said members individually each time said hand telephone is placed on or removed from said forked extensions. 55
5. In a telephone desk set, a hand telephone, a rigid support therefor, switching springs, a plurality of movable switching members associated with said support and directly operable by said hand telephone, a single means common to said switching members, said means being directly operable by each of said members, and means directly operable by said common means for operating said springs each time said hand telephone is manipulated. 60
6. In a telephone desk set, a hand telephone, a base containing switching springs, a plurality of formed extensions rigidly con- 65
- nected to said base and constituting a cradle for receiving said hand telephone, movable operating members extending midway between the prongs of each forked extension, and means operable by each of said movable members individually for operating said springs. 70
7. A portable telephone desk set comprising a base and a hand telephone, a cradle member integral with said base provided with a plurality of forked extensions for supporting said hand telephone, switching springs located within said base, and switching mechanism located within each of said forked extensions for operating said springs. 75
8. In a portable desk set, a cradle member, having upwardly projecting extensions for receiving a hand telephone, switching springs adapted to be operated by said hand telephone when the same is associated with and disassociated from the cradle, and a plurality of switching mechanisms located between said extensions for operating said springs. 80
9. In a telephone set, a cradle member having two oppositely located sets of forked extensions for receiving a hand telephone, movable members projecting upwardly from the center of each of said forked extensions, switching springs, and means operable by said movable members arranged to operate said springs. 85
10. In a telephone set, a cradle member having two oppositely located sets of forked extensions for receiving a hand telephone, switching springs, and switching members movably projecting upward from the center of each of said forked extensions for operating said springs. 90

In witness whereof, I hereunto subscribe my name this 20th day of August, A. D. 1925.

OTTO WEEBER.
